UNITED STATES PATENT OFFICE.

ERNEST J. KISS, OF FORT WAYNE, INDIANA.

AMALGAMATOR.

SPECIFICATION forming part of Letters Patent No. 681,232, dated August 27, 1901.

Application filed May 13, 1901. Serial No. 59,953. (No model.)

To all whom it may concern:

Be it known that I, ERNEST J. KISS, a citizen of the United States, residing at Fort Wayne, in the county of Allen, in the State of Indiana, have invented certain new and useful Improvements in Amalgamators; and I do hereby declare that the following is a full, clear, and exact description of the invention, which will enable others skilled in the art to which it appertains to make and use the same, reference being had to the accompanying drawings, which form part of this specification.

My invention relates to improvements in amalgamators employed for the purpose of extracting amalgamable metals—as gold, silver, and copper—from their ores.

The object of my present invention is to provide a cheap, simple, and efficient amalgamator of relatively large output capacity having a relatively large amount of amalgamating-surface, which is exposed to the ore-pulp in operation, provided with an improved means for agitating the ore-pulp and carrying it into and through the mercury, means for readily and conveniently draining off the mercury at pleasure from any and all of its containing-receptacles while the machine is in full operation, and means for exhibiting at all times the height of the mercury in each receptacle.

My improvement consists of a pair of horizontal copper cylinders rotatably mounted in an upright amalgamating-tank in vertical arrangement and in coöperation respectively with proper mercury-receptacles within said tank, the said cylinders being operatively connected by a proper driving and agitating chain; means for circulating the ore-pulp through said cylinders; means for conducting the ore to its discharge; means for draining the mercury from its respective receptacles, and means for determining its depth in such receptacles.

The principal novel feature of my present invention resides in the construction whereby a relatively large amalgamating-surface is secured and in the means for agitating the ore-pulp and bringing it into a positive contact with such surface.

Similar reference-numerals indicate like parts throughout the several views, in which—

Figure 1 is a cross-section of my improve-

ment, taken on the line $\alpha\alpha$ of Fig. 2, showing the relative arrangement of the operating mechanism and also broken away in part to show the hopper-conveyer and the means for discharging the ore after it has been acted upon by the machine. Fig. 2 is a plan view of the same with the cylinder-driving chain broken away in part to show the perforated perimeter of the cylinders, and showing the relative arrangement of the discharge-conveyer, the means for supplying the mercury to the containing-receptacles and for discharging it therefrom being omitted. Fig. 3 is a longitudinal central section of the same. Fig. 4 is a cross-section of one of the mercury-receptacles, showing the copper lining therefor. Fig. 5 is an enlarged detail of a small section of the driving-chain connecting the two revolute cylinders.

The amalgamating-tank 1, of any proper form and dimensions, preferably upright and rectangular, has a proper supporting-base 2 and a depressed or trough-like bottom 3, Fig. 1, and is provided with a triangular lateral extension 4 on one end thereof, forming an open-topped chamber 5, through which the ore-pulp is discharged after the completion of the amalgamating process. The inclined bottom of the chamber 5 is mercury-coated. Both the tank 1 and the chamber 5 are kept nearly filled with water 6, as shown in Fig. 1. In suitable fixed bearings 7, Fig. 3, in the upper portion of the said tank are rotatably mounted the horizontal axes 8, whose inner ends are rigidly fixed in suitable bearings 9, which are fixed in the opposite ends of the upper cylinder 10, of copper or brass, having upon its inner surface a spiral rib or flange 11 and having its periphery provided with numerous perforations 12 of proper size. Directly beneath this cylinder 10 and in coöperation therewith is arranged a proper mercury receptacle 13, whose ends are rigidly fixed to the respective ends of the tank 1. This receptacle, preferably of suitable metal, has a proper copper or brass lining 14, Fig. 4. Beneath this revolute cylinder 10 and in parallel arrangement therewith is rotatably mounted on suitable pivots 16, which are loosely mounted in the opposite ends of the said tank, a second brass or copper cylinder 15 of greater diameter than the said cylinder

10, also having its periphery provided with numerous perforations 17, and having upon the inner face of its perforated perimeter a fixed spiral flange 18, whose turns are in the 5 direction opposite to those of the said spiral flange 11, Fig. 3. Upon these two revoluble cylinders is loosely mounted a driving-chain 19, whose width is substantially equal to the length of the said cylinders. This chain is 10 formed of a series of short bar-links 20, whose adjacent ends are pivotally connected by a corresponding series of transverse rods or pins 21, the links being so arranged as to leave alternate open spaces 22 between the 15 same of sufficient size to freely permit the ore-pulp to pass through the same for the purpose hereinafter described. On the outer end of one of the short axes 8 is rigidly fixed a proper sprocket or drive wheel 23, which is 20 actuated from any proper source of power. The revolution of the upper cylinder 10 by means of the drive-wheel 23 will of course 25 actuate the lower cylinder 15 by means of the said chain 19. Directly below the lower cylinder 15 and in coöperative relation therewith is arranged a mercury-receptacle 24, of similar form and construction to the said receptacle 13, secured in a similar or other proper manner to the ends of the said tank 30 and provided with a similar copper or brass lining 25.

To the rear face and upper edge of the tank 1 is fixed a proper supporting-bracket 26, on which is rigidly mounted an ore-hopper 27, 35 having a discharge-spout 28 leading therefrom to the said tank and also having a horizontal spiral ore-conveyer 29 revolubly mounted therein and provided upon its outer end with a fixed drive-wheel 30. The said chamber 5 is separated from the interior of the tank 1 40 by means of the upright partition 31, except at the bottom of said chamber, as shown in Fig. 3.

In the trough-like bottom 3 of the tank 1, 45 which also contains a quantity of mercury 55 in use, is revolubly mounted a screw conveyer 32, having upon one end thereof a fixed pulley 33. This open-topped chamber 5 has at its rear end a delivery-chute 34, and also 50 has a rotatably-mounted pulley 35 in coöperative relation with said chute, Fig. 1. The said pulleys 33 and 35 are operatively connected by the driving-chain 36, which is provided with a series of fixed upright copper 55 blades 37 and is mercury-coated. These blades perform two functions. They serve to catch and hold any particles of precious metal and mercury that may be floating in the chamber 5, and they also serve to elevate the ore 60 as it settles to the bottom of the tank and carry it upward to the discharge-chute 34. The upper pulley 35 may be actuated in any proper manner. The bottom of the said chamber 5 has a vertical pocket 38, into which the ore is discharged by the said conveyer 32 65 and from which it is elevated and discharged from the machine by means of the said cop-

per-bladed chain 36. The means for either supplying mercury to the said receptacles or discharging it therefrom when the machine 70 is in operation is shown in Fig. 3 and consists of an upright pipe 39, having three lateral branch pipes. One pipe 40 is connected to the upper mercury-receptacle 13, another pipe 41 is connected to the lower mercury-receptacle 24, and the third pipe 42 is connected to the trough-bottom 43. At or near the outer end of the pipe 40 is arranged a cock 44, adapted to close the same. The pipe 39 is provided with a cock 45 above the cock 44 and with a cock 46 below the same, both of which are adapted to close the pipe 39. The pipe 40 is also provided with a mercury-gage 46'. The pipe 41 has a closing-cock 47 and a mercury-gage 48. The pipe 2 has a cock 51 85 and a mercury-gage 52. The pipe 39 also has a closing-cock 49 just below the said cock 47 and a closing-cock 50 just below the said cock 51.

The operation of my improvement thus 90 described is obvious and, briefly stated, is as follows: When the machine is started, by connecting the drive-wheels 23, 30, and 35 to any suitable motive power the said cylinders 10 and 15 will be rotated slowly, approximately 95 at the rate of from twenty to thirty revolutions per minute, and the endless carrier-chain 36 will travel over said pulleys 33 and 35 at a proper rate of speed, the said mercury-receptacles having been first supplied with a 100 proper quantity of mercury in the following manner: The operator closes the cock 46 and opens cocks 44 and 45 and then pours the mercury into the top of the pipe 39, from which it is conducted by gravity through the 105 pipe 40 to the receptacle 13 until the desired quantity is supplied, as indicated by the gage 46'. He now closes cock 44 and cock 49 and opens cock 46 and cock 47, after which mercury may be supplied to the central receptacle 24 through the pipes 39 and 41, the gage 48 continually registering the supply. He next closes the cocks 47 and 50 and then opens cocks 49 and 51, after which mercury may be supplied to the trough 3 through the pipes 39 115 and 42, the depth of which will be registered by the gage 52. The cock 51 is now closed. The manner of draining each of these mercury-receptacles either separately or simultaneously is too obvious to require any particular description. It is thus seen that either or all of the said mercury-receptacles can be supplied or drained at the pleasure of the operator without stopping or interfering with the operation of the machine. The ore-pulp 120 is now delivered in suitable quantities to the hopper 27, from which it is fed into the open top of the tank 1 by the screw conveyer 29, from which it is discharged downward upon the moving chain 19, which dips into and 125 passes through the body of mercury 53 in the receptacle 24, whereby its surfaces are kept continuously coated with a fresh supply of mercury. The two cylinders 10 and 15 have

their inner and outer surfaces also continuously coated with a fresh supply of mercury at each revolution thereof, as their perimeters dip into the body of mercury contained in the respective receptacles 13 and 24. When the fine ore-pulp is discharged upon the said chain 19, large portions of it after a contact with its amalgamating-surface will pass through the openings therein and into contact with the outer amalgamating-surface of the upper cylinder 10, after which it will drop through the perforations 12 of said cylinder into the interior thereof, whose surface is also continuously coated freshly by mercury in the manner above described. When this ore is thus received into the interior of the upper cylinder, it will be carried into and dragged through the body of the mercury 56 and will be carried from one end of the cylinder to the other by means of the spiral rib 11, thereby thoroughly agitating the same over this inner amalgamating-surface, after which it is gradually discharged through the said perforations and over the sides of the receptacle 13 and precipitated upon the upper perforated surface of the lower cylinder 15, whose outer and inner surfaces are also continuously coated freshly with mercury by passing at each revolution thereof through the body of mercury 53 in the receptacle 24. The ore-pulp also passes through the perforations in this cylinder, is carried from one end thereof to the other by the spiral rib 18 in a direction opposite to that given it in the upper cylinder, and is thus thoroughly agitated over both its outer and its inner amalgamating-surfaces, during which operation it is of course repeatedly dragged through the mercury in the receptacles 13 and 24, by which treatment the values are extracted from the ore. The surfaces of the chain 19 are of course kept freshly coated with mercury by continuously dipping into the body of mercury in the receptacle 24. After the ore has been discharged from the lower cylinder 15 it is received by the trough-like bottom 3 of the tank, which also contains a proper quantity of mercury 55. The ore is next discharged from the bottom 3 by the revolving conveyer 32 into the pocket 38. This pocket 38 is separated from the trough 3 by an upright partition 57, which serves to obstruct the ore in its discharge from the trough 3, and thereby retains it longer in the mercury-bath 53, and also contains a proper quantity of mercury 54. From this pocket the ore-pulp is carried upward to the discharge-chute 34 by the conveyer-chain 36, which is also kept freshly coated with mercury by passing through the said mercury-bath 55. The rubbing action of the ore-pulp against the said amalgamating-surfaces of the said cylinders and the said chains 19 and 36 will cause them to be kept clean, so that fresh mercury will constantly and readily unite with the said amalgamating-surfaces. My improvement thus affords a large amount of amalgamating-surface that is con-

stantly exposed to the ore-pulp and is a self-cleaning amalgamator that keeps the ore-pulp thoroughly agitated and keeps it passing through a series of mercury-baths before its final discharge from the machine. The said pocket 38 is readily drained by means of the cock 54. While the said chamber 5 and the conveyer-chain 36 may be omitted and the ore discharged directly from the trough 3, yet their employment as described is preferred.

Having thus described my invention, what I desire to secure by Letters Patent is—

1. In an amalgamating apparatus, an upright tank having a laterally-extended chamber on one end thereof; a pair of cylinders revolubly mounted one above the other in said tank; a driving-chain operatively connecting said cylinders; a pair of mercury-receptacles in co-operative relation with the said cylinders respectively as shown; a screw conveyer rotatably mounted in the bottom of said tank and dipping into a body of mercury therein; an inclined chain conveyer arranged in said chamber and adapted to discharge the ore from the machine; and means for actuating said screw conveyer and said conveyer-chain.

2. An amalgamator consisting of an upright tank; two mercury-coated cylinders rotatably mounted in said tank in vertical alinement; mercury-receptacles into which the said cylinders continuously dip; a mercury-coated driving-chain connecting the said cylinders and also dipping into one of said receptacles; means for rotating said cylinders; and means for discharging the ore from the tank.

3. In an amalgamator a stationary tank; a pair of metallic mercury-coated horizontal cylinders rotatably mounted therein in vertical alinement; an endless driving-chain connecting said cylinders; means for continuously coating the surfaces of said cylinders and said chain with mercury; and means for discharging the ore from the machine.

4. The combination in an amalgamator of a containing-tank; a pair of horizontal and vertically-alined cylinders whose perimeters are perforated as shown for the purpose specified, rotatably mounted in said tank; an open-link driving-chain connecting said cylinders; means for continuously coating said cylinders and said chain with mercury during their rotation.

5. An upright tank having upon one end a chambered extension; a pair of hollow perforated cylinders rotatably mounted in said tank in vertical alinement; an open-linked driving-chain connecting said cylinders; mercury-receptacles into which the said cylinders and said chain continuously dip during their rotation; a mercury-coated screw conveyer revolubly mounted in the bottom of said tank and adapted to feed the ore-pulp continuously forward into said chambered extension; a mercury-receptacle in said bottom into which the said conveyer continuously dips;

an inclined conveyer arranged in said extension and adapted to deliver the ore from the said screw conveyer to its discharge; means for rotating the said cylinders and the said 5 conveyers; and means for supplying mercury to the said machine, and discharging it therefrom without interfering with the operation of the machine.

Signed by me at Fort Wayne, Allen county, State of Indiana, this 7th day of May, A. D. 1901.

ERNEST J. KISS.
